(57) **CLAIM**

The ornamental design for roll out drawer with front and bottom panels, as shown and described.

DESCRIPTION

FIG. 1 is a perspective view of the roll out drawer with front and bottom panels;

FIG. 2 is a front elevational view of the roll out drawer with front and bottom panels of FIG. 1;

FIG. 3 is a rear elevational view of the roll out drawer with front and bottom panels of FIG. 1;

FIG. 4 is a right elevational view of the roll out drawer with front and bottom panels of FIG. 1;

FIG. 5 is a left elevational view of the roll out drawer with front and bottom panels of FIG. 1;

FIG. 6 is a top plan view of the roll out drawer with front and bottom panels of FIG. 1;

FIG. 7 is a bottom plan view of the roll out drawer with front and bottom panels of FIG. 1;

FIG. 8 is a perspective view of a second embodiment of the roll out drawer with front and bottom panels shown with an alternate wood grain panel pattern;

FIG. 9 is a front elevational view thereof;

FIG. 10 is a rear elevational view thereof;

FIG. 11 is a right elevational view thereof;

FIG. 12 is a left elevational view thereof;

FIG. 13 is a top plan view thereof; and,

FIG. 14 is a bottom plan view thereof.

The roll out drawer with front and bottom panels is shown with symbolic breaks in its length and width. The appearance of any portion of the article between the break lines forms no part of the claimed design.

The broken lines shown in the drawings are for the purpose of illustrating environmental subject matter and form no part of the claimed design.

1 Claim, 8 Drawing Sheets
